CLAIM

The ornamental design for a cabinet light, as shown and described.

DESCRIPTION

FIG. 1 is a front, right and top perspective view of a cabinet light, showing my new design;

FIG. 2 is a front view of the cabinet light in a use state;

FIG. 3 is a front, right and top perspective view of a controller of the cabinet light;

FIG. 4 is a rear, left and bottom perspective view thereof;

FIG. 5 is a front view thereof;

FIG. 6 is a rear view thereof;

FIG. 7 is a left side view thereof;

FIG. 8 is a right side view thereof;

FIG. 9 is an enlarged top plan view thereof; and

FIG. 10 is an enlarged bottom plan view thereof.

FIG. 11 is a front, right and top perspective view of a light of the cabinet light;

FIG. 12 is a rear, left and bottom perspective view thereof;

FIG. 13 is a front view thereof;

FIG. 14 is a rear view thereof;

FIG. 15 is a left side view thereof;

FIG. 16 is a right side view thereof;

FIG. 17 is an enlarged top plan view thereof; and,

FIG. 18 is an enlarged bottom plan view thereof.

The broken lines shown in the drawings illustrate portions of the cabinet light that form no part of the claimed design.
